UNITED STATES PATENT OFFICE.

AARON H. WOLFF, OF NEW YORK, N. Y.

DESIGN FOR A STOVE.

SPECIFICATION forming part of Design No. 29,240, dated August 16, 1898.

Application filed July 7, 1898. Serial No. 685,348. Term of patent 3½ years.

To all whom it may concern:

Be it known that I, AARON H. WOLFF, a citizen of the United States, residing at New York, in the county and State of New York, have invented and produced a new and original Design for a Stove, of which the following is a specification, reference being had to the accompanying drawings, in which—

Figure 1 is a front elevation of the stove 10 complete. Fig. 2 is a side elevation, and Fig. 3 a plan of the top plate.

The leading features of my design for a stove consist of the raised scroll, leaflet, and pearl ornaments disposed upon the surface 15 of the front, the door, and the sides, as shown, the pitted ground of the door within a rectangular pearl border, an oval border in the center of the door with a pitted ground, the diamond-shaped open-work apron to the front, 20 and the open-work circular and radial configurations and scroll ornaments of the top plate.

The design of the front and legs comprises 25 the scroll and leaflet ornaments a, a', a^2, a^3, a^4 , and a^5 , the pearl ornaments b , the diamond-shaped open-work apron c , and the ribbed ornaments d, d' .

The design of the door A comprises the scroll and leaflet ornaments e, e' , the pitted ground f within the rectangular pearl border 30 g , and the oval border h in the center of the door with a pitted ground h' .

The design of the side of the stove comprises the scroll and leaflet ornaments i, i' , the pearl ornaments k , and the frame and me- 35 dallion ornament l .

The design of the top plate comprises the open-work circular and radial configurations $n, n',$ and n^2 , and the open-work scroll ornaments o . 40

What I claim is—

1. The design for a stove substantially as shown and described.
2. In the design for a stove, substantially as shown and described, the design of the door. 45
3. In the design for a stove, substantially as shown and described, the design of the top plate.

Signed by me this 6th day of July, A. D. 1898.

AARON H. WOLFF.
